UNITED STATES PATENT OFFICE.

MELCHERD H. KUTCH, OF TERRE HAUTE, INDIANA.

VAGINAL DOUCHE-CUP.

1,074,368.

Specification of Letters Patent. Patented Sept. 30, 1913.

Application filed January 30, 1913. Serial No. 745,081.

To all whom it may concern:

Be it known that I, MELCHERD H. KUTCH, a citizen of the United States, residing at Terre Haute, in the county of Vigo and State of Indiana, have invented certain new and useful Improvements in Vaginal Douche-Cup, of which the following is a specification.

My invention relates to an improved vaginal douche-cup, and it has for its object an instrument of this character so constructed as to adapt it to the part to be treated, and to cause it to be supported in place thereat with the minimum of discomfort to the patient.

A further object of my invention is the construction of an instrument of this character which will offer no obstruction to the passage over it of the tip of the nozzle by means of which fluid is injected into the organ under treatment.

A further object of my invention is the construction of an instrument of this character which will drain the fluid injected into the organ under treatment and prevent such fluid from soiling the garments of the patient, or the bed-clothing, thus rendering it unnecessary to employ pads of rubber beneath the patient to prevent such soiling.

With these and other objects in view, my invention consists in the combination and arrangement of parts hereinafter fully described and set forth in the appended claims.

In the accompanying drawing illustrating the preferred embodiment of my invention, Figure 1 is a sectional view of the instrument when in position for use, that portion of the anatomy adjacent thereto being shown in dotted lines. Fig. 2 is a front view of the instrument in position for use, and Fig. 3 is a perspective view of the same.

Similar reference numerals indicate corresponding parts wherever they occur.

4 designates a cup which is provided in its bottom portion with an opening 5 from which extends a drainage tube 6 adapted to receive at its outer end a rubber tube 7. The rear wall of the cup at its upper edge is provided with a rearwardly projecting member 8 which is tongue-shaped and longitudinally concaved. This rearwardly extending or foot piece 8 is adapted to be introduced into the vaginal canal, which it dilates, thus permitting the easy introduction of the irrigating pipe, and assists in

supporting the instrument in place, and by reason of its curved construction permits the irrigating fluid to readily drain into the cup. A vaginal speculum may be introduced over the member 8, thus facilitating the introduction of fluid into the uterine canal or cavity.

Extending upward from each side wall of the cup 4, are fin-shaped wings 9, which are so shaped or constructed as to conform to the anatomy of the part with which they contact, and are made sufficiently strong to resist side pressure. The posterior edges of these wings are continuations of the lateral edges of the tongue 8 at the point of its attachment to the cup, and such edges of said wings curve upward, backward and then downward in the direction of the ilio-pectineal line of the pelvis. The anterior edges of the wings 9 are continuations of the posterior border after rounding a sharp curve at the tip. They then extend forward and downward, being first curved inwardly and then outwardly, terminating at a sharp curve on either side of the front border or wall of the cup's base. It will be noted that the exterior edges of the wings 9 present a concaved surface against which the inner portion of the thighs of the patient under treatment are pressed. They thus conform to the anatomy of the patient, and side pressure against the same assists in keeping the instrument in operative position.

As will be observed, the shape of the instrument is such that the upper edges of the cup portion are below the plane of the tongue 8, so that the cup offers no obstruction to the surgeon, and the draining of the irrigating fluid injected into such organ and its ready discharge is thereby facilitated.

In using the instrument, the patient is placed in a recumbent position and the tongue 8 of the instrument is introduced into the vaginal canal, the posterior border of the wings being then in apposition with the patient's body. The thighs are then flexed and fit the curve of the anterior borders of the wings and then by abducting the thighs the instrument is firmly fixed in position where it efficiently serves the purpose for which it is designed.

It will be noted that the anterior wall of the cup is below the inner end of the tongue-shaped member 8, and therefore offers no

obstruction to the introduction of the tip of the irrigating member.

While I have shown and described the preferred embodiment of my invention, it will be understood that I do not wish to be limited to the exact form shown and described, and that the appended claims are to be construed as broadly as the state of the art will permit.

10 Having thus described my invention, what I claim as new and desire to secure by Letters Patent, is:

1. In an instrument of the character described, a cup provided on its posterior wall 15 with a rearwardly projecting member, the upper edge of its anterior wall being disposed below the plane of said projecting member, and having upwardly extending wings extending from its side walls, and

provided with an opening in its bottom for 20 draining the same.

2. In an instrument of the character described, a cup provided on its posterior wall with a rearwardly projecting member, the upper edge of its anterior wall being disposed below the plane of said projecting member, and having upwardly extending wings extending from its side walls, said wings being curved and provided with concaved outer surfaces to conform to that portion of the anatomy against which they are placed. 25

In testimony whereof I affix my signature in presence of two witnesses.

MELCHERD H. KUTCH.
